E. B. SHIELDS & L. L. TYLER.
CONVEYING CABLE GRIP.
APPLICATION FILED SEPT. 23, 1914.

1,170,007.

Patented Feb. 1, 1916.

UNITED STATES PATENT OFFICE.

EDWARD B. SHIELDS AND LEWIS L. TYLER, OF TACOMA, WASHINGTON.

CONVEYING-CABLE GRIP.

1,170,007.

Specification of Letters Patent. Patented Feb. 1, 1916.

Application filed September 23, 1914. Serial No. 863,136.

To all whom it may concern:

Be it known that we, EDWARD B. SHIELDS and LEWIS L. TYLER, citizens of the United States, and residents of Tacoma, in the county of Pierce, State of Washington, have invented certain new and useful Improvements in Conveying-Cable Grips, of which the following is a specification.

This invention relates to mechanisms for securing a load to a moving conveying and supporting cable.

The objects of our invention are to provide a strong gripping action on the cable; to provide easy means of releasing said gripping action; to provide means permitting a liberal swinging action of the grip hanger in a plane at right angles to the direction of motion without interfering with the supporting sheaves of the cable; to provide a grip which does not raise the cable from the supporting sheave when it is passing thereover; and to provide for changes in the vertical angle between the cable and the grip hanger due to the sag of the cable or to swinging of the load in a longitudinal direction. We attain these and other objects by the devices, mechanisms and arrangements illustrated in the accompanying drawings, in which—

30 Figure 1 is a vertical cross-section of our improved conveying-cable grip showing the parts in position for gripping the cable and showing one of the supporting sheaves in dotted lines; Fig. 2 is a side elevation thereof; Fig. 3 is a view showing the grip in the position occupied thereby when the cable is at right angles to the hanger; Fig. 4 is a top plan of the grip; Fig. 40 5 is a cross-section thereof on the line 5—5 in Fig. 2; and Fig. 6 is a bottom view thereof.

Similar numerals of reference refer to similar parts throughout the several views. 45 The load is attached by a hook 1, or other suitable means, to the end of a horizontal arm 2 of the grip hanger. This arm 2 extends from the main part 3 of the hanger, said part 3 lying normally at an angle from the vertical as shown. The part 3 extends from adjacent the supporting cable down to the arm 2 and terminates at its upper end in a head 4. A cylindrical trunnion or pivot lug 5 extends horizontally from the head 4 and is provided with an axial hole passing

completely through it and the head 4. The grip is pivotally mounted on this pivot lug 5 and consists of a main jaw 6 mounted and freely turning on the said pivot lug, and a movable jaw 7 pivoted to said main casting 60 6 on an axis at right angles to the axis of the said pivot lug and parallel with the axis of the cable. The main jaw 6 has a horizontal pin 8 which forms the pivot of the said movable jaw 7 through which the said pin 8 65 passes. The main jaw 6 has a downwardly opening groove 9 extending from end to end, said groove being adapted to receive the cable and being preferably provided with corrugations corresponding with and 70 complementary to the strands of the cable. One side of the main jaw 6 is cut away at the center to receive the movable jaw, said cut part extending to the groove 9, said movable jaw 7 forming one side of said groove 9 at 75 the said central part of the grip.

The movable jaw 7 fits in the cavity in the main jaw 6 and has a pair of lugs 10 extending upward from each end, said lugs passing through suitable openings in the 80 main jaw and extending upward above the said main jaw as shown. Suitable holes are made in the upper ends of said lugs 10. It will be observed that the outer surface of the jaws 6 and 7 are cylindrical, having the 85 axis of the pivot pin 8 as its axis. The grooves in the supporting sheaves (shown in dotted lines) are formed on a similar curve, thus allowing a liberal swinging action between the said sheaves and the hanger. 90

A long hand lever 11 lies within the rear groove of the main part of the hanger 3, and extends down beyond the lower end thereof. This lever 11 is pivoted to the said hanger near its upper end by means of the pivot pin 12. A short lug 13 extends upward from the lever 11, above the said pivot pin 12, and has a slot therethrough in line with the axis of the pivot lug 5. A rod 14 passes through the hole in the pivot lug 5 100 and through the slot in the lever lug 13, and is provided with a suitable shoulder and nut whereby it is loosely secured to the said lug 13 to move therewith but to allow a slight relative movement to compensate for the circular motion of the lug. A yoke 15 is secured to the other end of the rod 14 and extends laterally therefrom and has a pair of rods extending from its ends and engaging the said lugs 10 of the movable jaw 7. 110

A spring 16 is secured to the lever 11 and engages the hanger 3 to cause the lever to swing outward therefrom and thus release the gripping movable jaw 7 from engagement with the cable. 5

A ratchet lever 17 is pivoted at 18 to the arm 2 of the hanger and is provided with suitable teeth 19 in its upper surface. A tooth 20 is formed on the lever 11 in such 10 position as to be adapted to engage the said teeth 19 in the lever 17. A spring 21 holds the lever 17 up so that the teeth 19 and 20 will always be held in contact with each other unless disengaged by manually 15 pulling said lever 17 down and thus releasing the said gripping lever 11. .

The operation of our improved conveying-cable grip is therefore briefly described as follows:—The cable lies within the groove 9 in the main jaw of the grip and, as soon 20 as the lever 11 is forced inward to the part 3, against the action of the spring 16, the jaw 7 is forced into compressive contact with the cable in the groove through the action of the lug 13, rod 14, yoke 15, and lugs 10. The lever 11 is held in said gripping position by the teeth 19 and 20 of the ratchet device. Now, when the cable is started, there will be a constant change in the vertical angle between the hanger and the cable 30 and this change is freely permitted because the entire gripping mechanism is mounted on the main pivot lug 5 of the hanger, and since the rod 14 which operates the gripping 35 jaw passes coaxially therethrough it is evident that any such relative movement will not affect the gripping action of the jaw 7. The motion of the cable will also cause a transverse swinging action of the load and 40 it is necessary to allow for this at the sheaves over which the cable passes. This is provided for by offsetting the hanger 3 by means of the arm 2, thus removing the part 3 from the path of the sheave, and by curving the under side of the grip jaws and the 45 groove of the sheave to a circular section. As a grip passes over a sheave it is necessary that the cable and grip be both in engagement with the sheave else the grip will be 50 raised and the cable will be torn from it and lie on the sheave. This is accomplished by having the groove 9 only as deep as the diameter of the cable, thus preventing the cable from being pulled loose from the grip. 55 As the cable bends over the sheave it is held only by the gripping jaws which are located centrally between the ends of the grip and there is therefore no tendency to pull it away from the grip on this score. The 60 groove 9 has vertical walls from its lower edge to one-half its depth and the cable lies loosely therein on each side of the gripped section and as it passes over a sheave the cable is drawn down from the ends of the 65 grip until the entire grip has passed the

sheave, but in so doing the gripped portion engaged between the jaws 6 and 7 is not moved.

Having described our invention what we claim is:

1. In a device of the class described, the combination with a main jaw adapted to engage a cable, a gripping jaw movably mounted on said main jaw and adapted to grip the cable between the main and movable jaws; a load-bearing device; a horizontal transverse pivot on said load-bearing device and passing through said main jaw, whereby the load-bearing device is connected to the jaw, and the jaw is permitted vertical angular motion relative thereto; an operating lever mounted on the load-bearing device; and means passing coaxially through said pivot and connecting said operating lever with said gripping jaw whereby said 75 jaw is actuated to clamp the cable. 80

2. In a device of the class described, the combination with a main jaw adapted to engage a cable; a gripping jaw pivoted to said main jaw and adapted to grip the cable between the main and movable jaws; a load-bearing device; an operating lever mounted on the load-bearing device; a horizontal transverse pivot on said load-bearing device and passing through said main jaw, whereby 90 the load-bearing device is connected to the jaw, and the jaw is permitted vertical angular motion relative thereto; and a rod 95 passing coaxially through said pivot and connecting said operating lever with said gripping jaw whereby said jaw is turned on its pivot to clamp the cable. 100

3. In a device of the class described, the combination with a pair of jaws pivoted together and adapted to engage and grip the cable between them; a load-bearing device; a horizontal transverse pivotal connection between said load-bearing device and said jaws, whereby the jaws are permitted a vertical angular motion relative thereto; and means for operating said jaws relatively to each other to grip the cable, said means also passing coaxially through said pivotal connection between the jaws and the load-bearing device whereby such vertical angular 110 motion of the jaws together will not affect their gripping action. 115

4. In a device of the class described, the combination with a main jaw having an open cable groove in its under surface, said jaw having a cavity centrally positioned between its ends and traversing said cable groove; a jaw positioned within said cavity and having a gripping surface forming a movable part of the cable groove and adapted to 120 clamp the cable between it and the main jaw; and a pivot pin lying parallel with and adjacent said cable groove and passing through both of said jaws whereby one is 125 pivoted to the other. 130

5. In a device of the class described, the combination with a main jaw having an open cable groove in its under surface, said jaw having a cavity centrally positioned between its ends and traversing said cable groove; a jaw positioned within said cavity and having a gripping surface forming a movable part of the cable groove and adapted to clamp the cable between it and the main jaw; a pivot pin lying parallel with and adjacent said cable groove and passing through both of said jaws whereby the gripping jaw is pivoted to the main jaw; a pair of upward extending lugs formed on the ends of said gripping jaw above said pivot pin and passing through the cavity in the main jaw and extending above said main jaw; a load-bearing device; a horizontal transverse pivot on said load-bearing device and passing through said main jaw centrally between its ends and above said first pivot, whereby the load-bearing device is connected to the main jaw, and the jaws are permitted vertical angular motion relatively thereto; an operating lever mounted on the load-bearing device; a yoke connecting said pair of upward extending lugs and passing across the axis of said second pivot; and a rod connecting said operating lever with said yoke and coaxially positioned relatively to the pivot between the main jaw and the load-bearing device, whereby said gripping jaw is actuated to clamp the cable.

6. In a device of the class described, the combination with a main jaw having a cavity centrally positioned between its ends and traversing said cable groove; a jaw positioned within said cavity and having a gripping surface forming a movable part of the cable groove and adapted to clamp the cable between it and the main jaw; a pivot pin

lying parallel with and adjacent said cable groove and passing through both of said jaws whereby the gripping jaw is pivoted to the main jaw; a pair of upward extending lugs formed on the ends of said gripping jaw above said pivot pin and passing through the cavity in the main jaw and extending above said main jaw; a load-bearing device; a horizontal transverse pivot on said load-bearing device and passing through said main jaw centrally between its ends and above said first pivot, whereby the load-bearing device is connected to the main jaw, and the jaws are permitted vertical angular motion relatively thereto; an operating lever mounted on the load-bearing device; a yoke connecting said pair of upward extending lugs and passing across the axis of said second pivot; and a rod connecting said operating lever with said yoke and coaxially positioned relatively to the pivot between the main jaw and the load-bearing device, whereby said gripping jaw is actuated.
